OIL BURNER APPARATUS

Wendell F. Austin, Medford, Mass.

Application March 26, 1935, Serial No. 13,029

2 Claims. (Cl. 158—28)

My invention relates to oil burner apparatus and it has for its object to provide an improved burner apparatus of this class which will be of simple and efficient construction.

To these ends I have provided an oil burner apparatus having the peculiar features of construction set forth in the following description, the several novel features of the invention being separately pointed out and defined in the claims 10 at the close thereof.

In the accompanying drawings:—

Figure 1 is a plan view, partly broken away, of an oil burner apparatus constructed in accordance with my invention.

Figure 2 is a section on line 2—2 of Fig. 1.

Figure 3 is a section on line 3—3 of Fig. 1.

Figure 4 is an end elevation of the delivery pipe of the apparatus shown in Figs. 1 and 3.

Figure 5 is a section on line 5—5 of Fig. 3.

The embodiment of my invention herein illustrated comprises a main housing or casing 10 constructed with three legs 11 by which it is supported from the floor in proximity to the fire-box of the furnace with which it is associated.

This casing provides a chamber 12 within which is arranged a fan 13 that is fast on a horizontal shaft 14 journaled in bearings provided on the casing at opposite sides of chamber 12.

The shaft 14 is, as usual, connected at its one end with the armature of an electric motor 15 by which it is driven in the direction of the arrow, Fig. 3, and at its opposite end with a gear pump 16 that is driven by it.

The chamber 12 has near its top a threaded outlet 17 into which is screwed the threaded end of a horizontal delivery pipe 18 whose opposite end portion, as usual, is disposed within the fire-box of the furnace.

Within delivery pipe 18, and near the outlet end thereof, is fixed a fan-like baffle comprising an apertured hub 19 and three radial vanes 20 whose outer ends snugly fit the interior of pipe 18. The aperture of hub 19 is occupied by a straight brass pipe section 21 which also extends through an aperture provided through the lower end of a bracket arm 22 which extends downwardly from the top wall of housing 10. The baffle 19—20 and bracket arm 22 support the straight pipe section 21 so that it is disposed centrally and longitudinally within the delivery pipe 18 and adjacent to the delivery end of the pipe 18 said pipe section 21 is equipped with a spray nozzle 23.

The end of pipe section 21 that is within chamber 12 is connected by a copper pipe 24 and oil

pressure regulating valve 25 with the outlet of the gear pump 16, the inlet of the latter being connected through a strainer 26 and pipe 27 with a supply of fuel oil.

Two of the vanes of the baffle 19—20 are formed each with an aperture within which is mounted one of a pair of electrode fixtures 28 whose electrode terminals 29 are supported with their ends in proximity to nozzle 23 as shown in Figs. 3 and 4. Each electrode 29 is connected by a high voltage cable or insulated conductor 30 with the usual transformer 31 mounted upon the exterior of casing 10, said two cables extending from fixtures 28 through pipe 18 and chamber 12 to the transformer, as will be clear from Figs. 15 3, 4 and 5, and the side wall of chamber 12 to which the transformer is fastened being constructed with an outlet 32 for each cable through which the latter extends from chamber 12 into transformer 31. Thus the two high voltage cables 30 are entirely enclosed and shielded.

The depending bracket arm 22 (Figs. 3 and 5) is made with a threaded aperture into which is screwed the threaded stem of a laterally projecting yoke-shaped hanger 33 by which the two cables 30 are supported in elevated positions above the fan wheel 13, said cables resting in the forked free end of the hanger as shown in Fig. 5 and being held or confined therein against accidental displacement while the burner is being handled or transported by the adjacent portion 34 of the top wall of the casing 10.

This portion 34 of the casing is a removable panel occupying an opening or hand-hole 35 formed at the top of the body portion of the casing, Fig. 1, and secured therein by two screws 36 and 37. The lower end of panel 34 rests upon a lug or shelf 38 formed with a threaded aperture to receive the screw 36 while the upper end of said panel is made with an off-set lug 39 formed with a longitudinal slot 40 that is open at one end.

The lug 39 overlies an adjacent portion of the body of the housing and its slot 40 is occupied by the screw 37 which extends downwardly therefrom through a plain hole 41 formed through said adjacent portion into a tapped hole provided in the upper end of the depending bracket arm 22 so as to hold both the latter and panel 34 fixedly in position.

Normally the bracket arm 22 and baffle 19—20 rigidly support the pipe section 21 and electrode fixtures 28 in their proper positions within the delivery pipe 18, but it will be clear that after removal of screws 36 and 37 together with panel 55

34, and after disconnecting pipe 24, the oil delivery pipe 21 together with the parts 19—20, 28, 29 and 22, may be withdrawn through handhole 35 for adjustment, repair, cleaning, or other attention, the cables 30 being removed from hanger 33 during this operation. Thus operations of this nature may be effected without disturbing the position of the casing 10 and delivery pipe 18.

10 One side wall of the body portion of the casing 10 is formed with an air inlet aperture 47 in communication with the interior of a hollow cylindrical damper sleeve 46 rotatably mounted within a semi-cylindrical hood bracket 42 fastened to 15 the apertured side wall of casing 10 by screws 42a. This hood bracket is made with an outer end wall provided with two tapped holes within which are mounted two set screws 45 whose inner ends are opposite the outer edge of damper sleeve 46 20 against which they are normally set up tight to hold the same against accidental rotative displacement.

The sleeve 46 is made with a plurality of parallel circumferential air inlet ports 43 through 25 which air is drawn from the outside atmosphere into sleeve 46 and from the latter through port 47 into the fan chamber.

It will be clear that the effective areas or sizes of the ports 43 may be varied by manual rotative 30 adjustment of sleeve 46 within the hood 42 while screws 45 are loose, and that the sleeve can be fixed in its adjusted position by setting the screws up tight.

By arranging the slots 43 circumferentially as shown the frictional resistance opposing the movement of the air therethrough is reduced to less than what it would be with the slots 43 disposed parallel with the axis of shaft 14 so that the described construction tends to improve the 35 efficiency of the burner.

It is a feature of the above described burner that the apertured arm 22 is made of such length

that when the screw 37 is tightened the baffle 19—20 is cramped or sprung sidewise within the outlet pipe 18 with the result that the oil delivery pipe 21 and all of the parts immediately associated therewith are fixed rigidly in position and 5 cannot vibrate or rattle.

What I claim is:

1. In an oil burner apparatus, a blower casing constructed with a fan chamber having a side wall made adjacent to its top with a laterally directed 10 air outlet and having a top wall made with a handhole; a fan disposed within the lower part of said chamber beneath said handhole; a panel normally closing said handhole; means removably fastening said panel to said casing; ignition devices mounted within said outlet with provision for removal through said chamber and handhole, and said devices including a circuit cable extending through said chamber and into said outlet, and means within said chamber for supporting 20 said cable above and out of engagement with said fan so that said panel normally serves to prevent disengagement of said cable from said supporting means but so that said cable is freed from such confinement by removal of said panel. 25

2. In an oil burner apparatus, a blower casing constructed with a fan chamber having a side wall made adjacent to its top with a laterally directed air outlet and having a top wall made with a handhole; a fan disposed within the lower part 30 of said chamber beneath said handhole; a panel normally closing said handhole; means removably fastening said panel to said casing; a yoke-shaped bracket within said chamber for supporting an electric cable of the ignition devices 35 of the apparatus above and out of engagement with said fan so that said cable is normally confined within said yoke-shaped bracket by said panel but is freed from such confinement by removal of the latter. 40

WENDELL F. AUSTIN.
